JAMES CHASE, OF ROCHESTER, NEW YORK.

Letters Patent No. 100,855, dated March 15, 1870.

IMPROVEMENT IN WOOD-TURNING LATHE

The Schedule referred to in these Letters Patent and making part of the same

To all whom it may concern:

Be it known that I, JAMES CHASE, of Rochester, in the county of Monroe, and State of New York, have invented certain new and useful Improvements in Wood-Turning Lathes; and I do hereby declare that the following is a full, clear, and exact description thereof, reference being had to the accompanying drawings making part of this specification, in which—

Figure 1 is a plan view of my invention.

Figure 2 is a side elevation of a portion of the head-block C and connected parts.

Figure 3 is a transverse section, showing those parts to the left of the dotted line x, fig. 1.

Figure 4 is a similar section, showing those portions to the right of the dotted line y, fig. 1.

Figure 5 is a vertical central section of the tail-block B.

Figure 6 is an inverted view of a portion of my invention, representing the manner of securing the tail-block.

Figures 7 and 8 are details.

The object of my invention is to provide an automatic machine for turning all kinds of ornamental circular work used in furniture and other articles; and

Its nature will be understood by reference to the specification and drawings.

To enable others to make and use my invention, I will describe its construction and operation.

Upon the horizontal bed A I provide the head or spindle-block C and tail-block B, arranged similarly to an ordinary lathe.

The slide-rest D is fitted to move easily upon the ways of the bed A, and when in operation, is driven by the feed-screw a by means of the shear-nut b, figs. 1, 3, and 4.

Levers c and d are cast upon the two parts of the nut, which are pivoted to the slide-rest.

The spring e, acting upon the upper end of these levers, holds the nut out of gear, as shown in fig. 3.

The cam f, attached to the lever g by means of a spindle, having bearings in a suitable portion of the slide-rest, separates the levers and throws the nut into gear, as shown in fig. 4.

The feed-screw is driven by any convenient arrangement of gearing or belts from the main spindle C'.

In the stock h, figs. 1, 3, and 4, properly secured to the slide-rest, I fasten a roughing-tool, h', which reduces the stock to a circular form previously to its entering the die or rest E. This tool is so adjusted that the stick shall just fit the rest E, whereby it is prevented from "chattering" or springing by the action of the finishing-knives. The rest E is made detachable from its stock, and may be replaced by others of different diameters.

For finishing the work, I use either the rotary pat-

tern-knife F, figs. 1, 3, and 4, its shaft running in proper bearings upon the slide-rest, and operated by means of the pinion i meshing into the fixed rack H, or the pivoted rolling tool G.

The rotary pattern-knife shaft is controlled in its vertical movement by a pattern, F', and its inner end runs in a pivoted box, as fully described in my patent of March 26, 1867.

The rack H is longitudinally adjustable in the swinging arms H', and is secured by the clamping-screws j, by means of which any adjustment of the pattern-knife to a particular point in the work, less than the pitch of one tooth of the pinion i, may be obtained by loosening the screws j', turning the pattern-knife to the required point while the slide-rest remains stationary, or *vice versa*, and clamping the rack again.

Parts L, figs. 1, 2, and 3, cast or otherwise secured to the head and tail-blocks, and having their inner faces perpendicular to the ways of the lathe, guide the pivoted arms H', whereby all end motion caused by the thrust of the carriage and pattern-knife is prevented.

The stock G' of the finishing-knife G is fitted to turn in the box I, at right angles or nearly so to the work, and this box is pivoted to the slide-rest at the point n, figs. 1, 3, and 4, parallel or nearly so with the work. The knife G is thus permitted a rolling movement in the box I, and a vertical movement about the center n.

These movements are controlled by the patterns o and p, secured to the beam J, as shown in fig. 2, whereby the finished work will be an exact copy of the outline of the rear pattern o by means of the arm q resting upon it and secured to the tool-stock G', and the knife G is rolled to prevent gouging when moving over curves or inclines, by means of the bent arm q', secured to q, and resting upon the pattern p.

The office of the tool G is chiefly to finish the plain curves and tapers in the work, acting in connection with the rotary pattern-knife F', which executes the sharp and more difficult portions. This is an important feature in my invention, since I am enabled to use the inexpensive knife G, which is easily kept in order for a large portion of the work, whereas, the pattern-knife F is both costly in construction and difficult to sharpen, and its use is not necessary except upon the more intricate curves and ornaments.

The patterns o, p, and F' are consequently so formed and adjusted with relation to each other that at the moment the pattern-knife F drops away from the work, the knife G descends and begins to operate, and *vice versa*.

The beam J, figs. 1, 2, 3, and 4, made longitudinally adjustable upon suitable lugs cast upon the head and tail-blocks B and C, as shown more clearly in fig.

2, supports the patterns *o* and *p*, center-rest *K*, and tenon-attachments *M*.

The rest *K*, shown in a raised position in fig. 3, is used to steady long work after the tool has passed over a portion of it, and is hinged at the rear to a plate, *r*, made longitudinally adjustable upon the beam *J*.

Friction-rollers, *t*, fig. 3, are provided upon this rest, to clamp the stick, the bearings of which are adjustable transversely to the work, to accomodate different diameters.

It is necessary that these rollers bear upon the stick somewhat above its center, as indicated by the dotted circle in fig. 3, in order to obtain a downward pressure at nearly opposite points, and since the vertical position of the rollers must be raised on this account for work of different sizes, I provide a vertically adjustable stop, *t'*, screwed into the rest *K*, and resting at its base upon the way of the lathe. The adjustment is obtained by screwing the stop in or out of the rest.

A spring, *s*, is riveted to the stop *t'*, and being bent in a suitable shape at the lower end catches under the flange of the way and retains the rest in its place.

In many kinds of ornamental work tenons are provided at one or both ends of the stick, to secure the parts together. For the purpose of forming such tenons, I provide the tool-stock *M*, one or more, as desirable, resting upon the supporting-beam *J*. These tool-stocks are hinged to the plates *r*, made longitudinally adjustable upon the beam *J*, and may be thrown back, as shown at the right hand of fig. 1, when not in use.

The knife *M'* is secured to the stock by a clamp, *u*, and a suitable throat-plate, *u'*, is also attached, to prevent the knife from gouging.

The stock *M* is made vertically adjustable by means of the slotted stop *z*, clamped upon the stock by a screw, and having a set-screw, *a'*, in a flange cast upon its base, as shown in fig. 1. The adjusting-screw *a'* coming in contact with the way of the lathe, determines the size of the tenon.

In operating wood-lathes having a fixed tail-center, there is always a difficulty in preventing the wood from charring at the point of bearing. To obviate this, I allow the tail-center to revolve with the stick in suitable bearings. The hollow sliding spindle *d'*, fig. 5, is cored out to receive a bearing of Babbitt metal at each end.

The center *b'* is turned tapering at these points, and is adjusted in the usual manner by a set-screw at the rear. It will be observed that should these bearings become worn out, they may be easily renewed by placing the center at its farthest rear position, and filling them again with metal.

For convenience in re-babbitting, the spindle *d'* may be made in halves, as shown in fig. 8, or caps may be screwed upon its ends, made removable to receive the metal. A nut, *f'* is cast upon the sliding spindle *d'*, open at the bottom, as shown, for convenience in removing it from the tail-screw *u'*.

This nut may also be renewed by filling the recess *e'* with Babbitt metal.

For the purpose of quickly adjusting the tail-block *B* upon the ways and holding it securely, I attach a clamping-yoke, *P*, figs. 5 and 6, by means of the ordinary bolt and hand-nut *P'*.

Suitable projecting-teeth, shown by dotted lines in fig. 6, upon the clamping-yoke, engage the ratcheted racks *T* formed upon the lathe-bed.

This yoke is accurately fitted between lugs *c'*, cast upon the tail-block, whereby pressure upon the latter, caused by forcing the tail-center into the work, is communicated directly to the rack and lathe-bed.

In fig. 7 I have shown a plan of adjusting the pattern-knife *F* to sticks of different diameters. The box *r''* is pivoted to the plate *p'* cast upon the rocking spindle *m*, figs. 1 and 7.

A suitable set-screw, *w*, moving in a curved slot secures the adjustment, as shown by full and dotted lines in fig. 7.

This is a very desirable arrangement, since where there is much variation in the size of the work, it has heretofore been necessary either to change the knife-head or elevate the pattern *F'*, the former of which is inconvenient, and the latter in many cases impossible, owing to its distance from the pivoting-point *n*.

A pivoted V-tool, *W*, fig. 1, controlled by a pattern, *X*, may be used, if desirable, to precede the finishing-knives.

What I claim as my invention, and desire to secure by Letters Patent, is—

1. The finishing-knife *G*, having both a vertical and a rolling movement produced by patterns, when used in connection with the rotary pattern-knife *F*, for the purposes set forth.

2. In combination with the pivoted arms *H'* of the yielding rack *H*, the vertical guides *L*, for the purposes specified.

3. The box *r''* of the rotating pattern-knife shaft, when attached to the hinged supporting-plate *p'* by means of the pivot *z'* and clamping-screw *w*, for the purposes specified.

4. The hinge-plate *r'*, when made horizontally adjustable upon the beam *J*, in combination with the stock *M* of the tenon-knife, substantially as and for the purposes set forth.

5. The adjustable spring-locking stop *t'*, in combination with the hinged center-rest *K*, operating substantially as described.

6. The adjustable live tail-center *b'*, when provided with a tubular sliding box, *d'*, so constructed as to admit of tapering babbitted bearings at each end, for the purposes set forth.

7. The clamping-yoke *P*, fitted between suitable lugs, *c'*, upon the tail-block *B*, in combination with the ratcheted rack *T*, substantially as set forth.
